UNITED STATES PATENT OFFICE.

EDWARD P. COLE, OF CHICAGO, ILLINOIS, ASSIGNOR TO COLE MANUFACTURING COMPANY, OF CHICAGO, ILLINOIS, A CORPORATION OF ILLINOIS.

CABINET HEATER.

Application filed September 4, 1925. Serial No. 54,405.

My invention has reference to heaters of the type commonly known as cabinet heaters and wherein the heating unit or stove is enclosed in a cabinet or casing which provides a space around the heating unit or stove, through which air is circulated and heated.

The principal objects of my invention are to improve the construction of cabinet heaters; to adapt the cabinet for use with stoves of various types and sizes; to utilize stoves and cabinets which are separate and independent units and merely combined by mounting the stove in the cabinet; to permit a stove to be easily and conveniently introduced into the completed cabinet; to afford adjustment for properly locating a stove in the cabinet; to make the doors of the cabinet independent of the doors on the stove so that the latter doors do not have to occupy a definite or fixed position; to afford a large extent of direct radiation when desired; to permit variations in the arrangement of the smoke outlet; to operate the door of the heater or stove by the opening and closing movement of the cabinet door; and in general to provide a simple, convenient and attractive cabinet of a universal character which will readily accommodate heaters of different types and sizes without requiring extensive changes or special construction.

On the drawings, Fig. 1 is a perspective view looking at the front of my improved cabinet, with some of the doors opened to disclose the stove or heater installed therein;

Fig. 2, a top view of the heater cabinet;

Fig. 3, a transverse sectional view through the cabinet and stove;

Fig. 4, a perspective view of the support for the stove or heater;

Fig. 5, a detail view showing the manner of mounting the support;

Fig. 6, a fragmentary sectional view showing the manner of securing the stove or heater onto the support;

Fig. 7, a perspective view of a fragmentary portion of the stove and the strap thereon which is used in securing the stove on the support;

Fig. 8, an enlarged sectional view on the line 8—8 of Fig. 1;

Fig. 9, a perspective view of one end of

the cross bar which is located at the front 55 of the cabinet; and

Fig. 10, a sectional view taken substantially on the line 10—10 of Fig. 2 showing the arrangement of the smoke outlet.

Referring to the drawings the reference 60 numeral 1 indicates the base of the cabinet which is in the form of an open rectangular frame having legs 2 at the corners with corner members or posts 3 extending upwardly from the corners thereof and supporting a grilled top 4 preferably of ornamental design. The back and side walls of the cabinet comprise upper and lower sections 5 and 6 respectively which are secured to and extend between the corner posts 3 70 and between the top 4 and the base 1, the section 5 being in the form of a solid panel, while the lower section 6 which is shorter than the section 5 is preferably in the form of an ornamental grill with openings therethrough for admitting air into the cabinet 75 for circulation upwardly therethrough.

The front of the cabinet is provided with a removable cross bar 7 substantially at the same elevation as the juncture line between 80 the wall sections 5 and 6, which said bar extends between the front corner posts 3 and is formed at the opposite ends with lugs or wing portions 8 and 9 respectively which fit within the corner posts 3 and are provided 85 with apertures 10 and 11 respectively for the bolts 12 and 13 which serve to secure the cross bar 7 to the corner posts.

A pair of doors 14 are hinged as at 15 to the corner posts 3 at opposite sides of 90 the cabinet front so as to close the front opening between the top of the cabinet and the cross bar 7, these doors being in the form of solid panels which may be lined if desired to provide an air space therein as 95 indicated by the rear view of the open door 14 in Fig. 1. The front opening between the base 1 and cross bar 7 is closed by a pair of doors 16 which are hinged to the corner posts 3 and are preferably in the form of 100 a grill matching the sections 6 and formed with openings for admission of air into the heater cabinet.

For supporting a stove or heater in the cabinet of rectangular frame or support 17 105 is provided which is mounted on lugs which extend inwardly from the base 1 at suitable points therearound. There are two sets of

5 lugs whereby the support 17 may be arranged at different elevations, the upper set being indicated by the reference numeral 18 while the lower set, of which only one is 10 shown in Fig. 5, are indicated by the reference numeral 19. In the present construction each set comprises three lugs located respectively at the opposite sides of the heater casing and at the front, the side lugs being located somewhat nearer to the back of 15 the cabinet than they are to the front as shown in Fig. 3.

10 The support 17 is smaller in size than the opening through the base 1 so as to afford 15 an air passage therearound and is provided at opposite sides with ears 20 which are adapted to optionally engage the side lugs 18 or 19, and this support has an apron 21 20 at the front which is adapted to be secured to either of the lugs 18 or 19 at the front 25 of the base 1. The side ears 20 are provided with slots 22 and the apron 21 with a slot 23 while the lugs 18 and 19 have apertures 28 through which bolts 25 are passed for 30 securing the support 17 on the lugs 18 or 19.

35 In order to afford additional elevational adjustment for the stove in the heater cabinet, the support 17 is arranged with the side ears 20 and the apron 21 vertically offset from the stove supporting surface, this being accomplished in the present case by forming the support 17 with a marginal flange 26 having the ears 20 and apron 21 at the edge of the flange as shown in Figs. 4 and 5 so that by reversing the support 17 40 in its mounting on either set of lugs 18 or 19, the elevation of the supporting surface of the support 17 may be varied as indicated by the dotted lines in Fig. 5.

45 The stove 27, in view of the construction of this cabinet and the adjustability of the support 17, is not confined to a particular type or size. In other words it is not necessary to use a stove which is specially constructed for use in this heater cabinet but it is possible for various stoves to be used therein. Purchasers of a cabinet of this type, therefore, may conveniently use therein a stove which they already have as the 50 support 17 may be arranged at the proper elevation for such stove and the doors 14 and 16 at the front of the cabinet affords access to the fuel and ash pit doors of the stove without necessitating a particular location of such fuel and ash pit doors. In the present case the ash pit door is indicated at 55 28 and it will be observed that this is conveniently accessible through the doors 16 and the fuel door which in the present case is shown at the top of the stove 27 and indicated by the reference numeral 29 is accessible through the doors 14.

60 As a further means for affording free access to the opening at the top of the stove 27, the cabinet top 4 is formed at the front

65 with a large opening which is closed by a door 30 and the latter is hinged at 31 to swing upwardly and rearwardly as indicated in Fig. 1. The door 29 of the stove may for convenience be connected by the link 32 with the door 30 so that when the latter is opened the door 29 is likewise opened and held in the upraised position and when the door 30 is closed the stove door 29 is closed thereby.

70 The arrangement of the cabinet with the removable cross bar 7 and with the front which is entirely open when the doors 14 and 16 are opened, makes it possible for a stove to be conveniently installed in the heater cabinet, and the provision of the door 30 further facilitates the introduction of the stove into the cabinet. Furthermore, it is sometimes desirable to utilize the direct radiation of the stove 27 and it will be observed that the opening of the doors 14 and 16 75 completely exposes the front of the stove 27 and presents a large area thereof for direct radiation.

80 Any convenient means may be provided for securing the stove 27 onto the support 17. In the present construction a slot 33 is provided at each corner of the support 17 to receive a bolt 34 which is passed through an aperture at one end of a clamping plate or bar 35 and a plurality of correspondingly arranged straps 36 are secured on the underside of the stove 27 to receive the ends of the bars 35. When these bars 35 are engaged in the respective straps 36 and locked in position by the bolts 34 the stove 100 is held thereby securely in place on the support 17, and as the latter is bolted to the base 1 the stove is firmly fastened in the heater cabinet.

105 Provision is made exhausting the smoke from the stove 27 by forming the cabinet top 4 with an opening 37 substantially at the proper position for a pipe 38 to lead directly up therethrough from the smoke outlet 39 at the back of the stove 27. The opening 37 in the cabinet top is preferably somewhat larger than the usual pipe which is employed so that there may be some variation in the position of the stove outlet 39. Furthermore, as the top of the stove is 110 adapted to be positioned some distance from the top of the cabinet, which distance may be varied by reversing the support 17 or changing the mounting of same on the supporting lugs 18 or 19, a sufficient distance 115 may be provided between the outlet 39 and the top of the heater cabinet to accommodate an offset in the pipe 38 if the relative position of the opening 39 in the stove and the opening 37 in the top of the heater cabinet should require such an offset in the pipe 38.

120 From the foregoing it will be observed that I have provided a heater cabinet which is not limited to use with a particular type 125

or size of stove, or to a stove of special construction, but it is capable of accommodating stoves of various types and sizes, and further that in view of the fact that the entire front of the cabinet may be opened up, a purchaser of a cabinet of this type can easily install his stove therein.

While I have shown and described my invention in a preferred form, I am aware that various changes and modifications may be made without departing from the principles of my invention the scope of which is to be determined by the appended claims.

I claim:

15 1. The combination with a heater cabinet of adjustable means carried by the upright walls of the cabinet whereby stoves of different sizes may be individually secured in optional positions in the cabinet, said cabinet being provided with openings at the top and bottom affording air circulation through the cabinet around the stove.

2. The combination with a heater cabinet of a stove support carried by the upright walls of the cabinet adjacent the lower end thereof for securing a stove in the cabinet, and means for varying the position of said support in the cabinet for accommodating stoves of different sizes, said cabinet having openings at the top and bottom affording air circulation through the cabinet around the stove.

3. The combination with a heater cabinet having openings at the top and bottom for affording air circulation through the cabinet, of a supporting frame secured to the cabinet walls adjacent the lower end for supporting a stove thereon, said supporting frame being adjustable to different elevations in the cabinet.

4. The combination with a heater cabinet of a reversible support on the cabinet adjacent the lower end for supporting a stove in the cabinet at different elevations, said cabinet being provided with openings at the top and bottom affording air circulation through the cabinet around the stove on said support.

5. The combination with a heater cabinet having openings at the top and bottom for affording air circulation therethrough, of a stove support which is reversible for varying the elevation of a stove thereon, and means adjacent the bottom of the cabinet for optionally mounting the reversible support at different elevations.

6. The combination with a heater cabinet, of a stove support having vertically offset attaching means for reversibly mounting the support at different elevations at the lower end of the cabinet, said cabinet having openings at the top and bottom for affording air

circulation through the cabinet around the stove.

7. The combination with a heater cabinet, 65 of two sets of supporting lugs adjacent the lower end thereof, a support having corresponding vertically offset ears for optionally attaching the support in reversed positions on either set of said lugs so as to support a 70 stove at different elevations in the cabinet, said cabinet being provided with openings at the top and bottom affording circulation of air through the cabinet around the stove on the support.

75 8. The combination of a heater cabinet having an open side for admitting a stove into the cabinet, a stove support extending inwardly from the side walls of the cabinet, a removable bar extending across the open- 80 ing above the level of the stove support, and doors arranged respectively above and below the bar for closing the open side of the cabinet.

9. A heater cabinet having a side opening 85 and a top opening forming a continuation of the side opening, and doors hinged on the cabinet for closing the top and side openings.

10. The combination of a heater cabinet 90 having a stove-support projecting inwardly from the side walls of the cabinet, and clamping plates on the support for securing a stove on the support.

11. The combination of a stove having a 95 smoke outlet, a cabinet enclosing the stove and having an opening spaced from the said smoke outlet, and a pipe leading from said smoke outlet and through and spaced from the edge of the said opening of the cabinet. 100

12. In combination, a heater cabinet comprising a leg supported base having an open bottom, a cabinet body rising from the base and provided with doors constituting one side of the cabinet body, stove supports ex- 105 tending laterally inward from the side walls of the cabinet body, and a stove housed within the cabinet and supported upon the stove supports and insertable and removable through the open side of the cabinet body 110 when the doors are open.

13. A heater cabinet comprising a leg supported base having an open bottom, a cabinet body rising from the base, stove supports extending laterally inward from the side walls of the cabinet body, a stove housed within the cabinet and removably supported upon the stove supports, the cabinet body having a side opening extending 115 from the top to the bottom thereof to permit the insertion and removal of the stove, and a displaceable closure for said opening. 120

EDWARD P. COLE.
